UNITED STATES PATENT OFFICE.

ADELBERT L. TRAVER, OF PHILMONT, NEW YORK, ASSIGNOR TO AMERICAN
RAVELLER CO., OF PHILMONT, NEW YORK, A CORPORATION OF NEW YORK.

TRIMMING AND CLEANING ATTACHMENT.

1,116,170.

Specification of Letters Patent.

Patented Nov. 3, 1914.

Application filed September 24, 1913. Serial No. 791,665.

To all whom it may concern:

Be it known that I, ADELBERT L. TRAVER, a citizen of the United States, residing at Philmont, in the county of Columbia and State of New York, have invented new and useful Improvements in Trimming and Cleaning Attachments, of which the following is a specification.

The invention relates to a trimming and cleaning attachment, and more particularly to the class of trimming attachments with an oscillatory cleaning brush for use on seaming or looping machines, the attachment being especially designed to be applied to the improved looping machine forming the subject matter of Letters Patent No. 1,054,724, issued March 4, 1913.

The primary object of the invention is the provision of an attachment of this character wherein the seams of hosiery and knit underwear formed from looped fabric may be trimmed and cleaned prior to the uniting of the seams while the sewing machine is in operation, thereby cutting the surplus knitted fabrics and cleaning out the half stitches so that as the work enters the sewing needle and is sewed there is no surplus waste left in the fabric when sewed together, and in this manner avoiding ridges at the seams of the finished article.

Another object of the invention is the provision of an attachment of this character wherein the same can be mounted upon the machine for sewing looped fabrics so that on uniting the fabrics thereby the seams produced will be trimmed and the surplus threads or loops will be removed under the action of the brush which serves to clean the seams, thereby avoiding ridges at any point of the same.

A further object of the invention is the provision of an attachment of this character wherein the brush and knife are actuated in a novel manner simultaneously with the working of the machine for sewing the looped fabrics together, the attachment being of novel construction to assure the perfect trimming of the fabrics at the seams and for cleaning such seams to remove waste threads or loops therefrom.

A still further object of the invention is the provision of an attachment of this character which is extremely simple in construction, thoroughly reliable and efficient in operation, and inexpensive in manufacture.

With these and other objects in view, the invention consists in the construction, combination and arrangement of parts as will be hereinafter fully described, illustrated in the accompanying drawing, and pointed out in the claims hereunto appended.

In the drawings:—Figure 1 is a top plan view of a machine for sewing looped fabrics, showing the attachment constructed in accordance with the invention applied. Fig. 2 is a front elevation thereof. Fig. 3 is a vertical transverse sectional view on the line 3—3 of Fig. 1. Fig. 4 is a bottom plan view of the attachment. Fig. 5 is a sectional view on the line 5—5 of Fig. 3. Fig. 6 is a view 70 similar to Fig. 2, looking toward the opposite side of the attachment. Fig. 7 is a perspective view of the trimming knife and stem.

Similar reference characters indicate corresponding parts throughout the several views in the drawings.

Referring to the drawings in detail, the attachment comprises a bracket 10 which is bolted or otherwise fixed to the head A of the machine for sewing looped fabrics, the details of which are set forth in Letters Patent hereinbefore referred to, the head being supported by the arm B of the frame C of the machine, and rotatable on said head is 85 the point cylinder D having the peripherally disposed points E upon which the looped fabrics are impelled in the usual manner. This point cylinder D is rotated through the medium of connections with a horizontal shaft F which is driven by means of a belt pulley G carried thereby. Formed on the bracket 10 is a boss or stud 11 on which is engaged the intermediate eye 12 formed on a supporting arm 13 which is 95 provided with outer eye terminals 14 and 15, the stud 11 being formed with a groove 16 in which engages a set screw 17, the latter being threaded in the eye 12 so as to lock the arm 13 thereon against swinging movement. 100

Formed on the outer eye terminal 15 is a yoke or crane 18, while rotatably and slidably fitted in the said eye terminal 15 is a knife carrying stem or shaft 19, the same being also rotatably and slidably fitted in a bearing 20 formed on the crane 18 in alignment with the eye terminal 15, the stem or shaft 19 being fitted at its lower end with a trimming knife 21, the latter being detachably connected to a foot 22 formed with a 110

sleeve 23 adapted to surround the stem or shaft 19, and carries a set screw 24 which locks the sleeve thereon.

Carried by the other eye terminal 14 of the arm 13 is a gear casing 25 which is formed with a hollow stem 26 fitted in the eye terminal 14 and held fast therein by means of a set screw 27 carried by the terminal. Passed through the hollow stem 26 is an oscillating shaft 28 having fixed thereto a beveled gear 29 adapted to work within the casing 25, and with this gear meshes a beveled pinion 30 fixed to a rotatable brush carrying shaft 31 which is supported in 15 slideable and rocking bearings 32 and 33 respectively, the casing being cut away in its side wall to form a space for the rocking bearing 33 which is supported upon pivots 34 adjustably mounted in out-turned wings 20 35 integral with the side wall and at opposite sides of the cut away portion therein, while the sliding bearing 32 is held within a guideway 36 formed in the side wall of the casing diametrically opposite the cut 25 away portion therein. The sliding bearing 32 is of the split type which are formed with extensions 37 providing a sleeve on which is fitted the hub portion 38 of a hood 39 for the cleaning brush 40 which is detachably fixed 30 to the end of the shaft 31 extended within the hood 39. Rising from the casing 25 above the guideway 36 are posts 41 supporting a cross plate 42 through which works an adjusting screw 43, the upper 35 threaded end 44 of which is engaged by a knurled adjusting nut 45 which works against the plate 42, the screw 43 being extended between the posts 41 and is swiveled in any suitable manner in the sliding bearing 32 so that the brush can be adjusted with 40 relation to the point cylinder D of the sewing machine. Surrounding the screw 43 is a coiled expansion spring 46, one end of which works against a cotter pin 47 engaged 45 in the screw, and its opposite end works against the plate 42, the spring being designed to act as a tensioning device on the screw when being lowered on adjustment of the nut 45 threaded thereon. The hub portion 38 of the hood 39 carries a set screw 48 which engages the sleeve 37 to prevent the turning of the hood and permits the proper 50 adjustment thereof.

Suitably fixed to the shaft 28 at the upper end thereof is a lever 49, while fixed to the knife carrying shaft or stem 19 is a lever 50, the latter being connected to the said lever 49 through the medium of a link 51 so that the said levers will work in unison. 55 The lever 49 has connected thereto by means of a universal joint 52 an operating rod 53, the same being also eccentrically connected by means of a universal joint 54 to a rotatable disk 55 centrally fixed to the 60 driving shaft F of the sewing machine so

that on the rotation of the said shaft oscillatory movement will be imparted to the levers 49 and 50 for the working of the knife 21 and the brush 40 simultaneously with each other.

At one side of the bracket 10 is adjustably connected a foot 56 supporting a guide plate 57 which is arranged vertically at one side of the knife 21 and is of the shape shown to deflect the trimmings severed by the knife 75 from the looped fabrics which is united or stitched together during the operation of the machine for sewing the said fabrics together, it being understood of course that the point cylinder D of the said machine is 80 actuated whereby a step by step rotary movement is imparted thereto while the machine is in operation. The foot 56 is formed with a bifurcation 58 in which engages a threaded stud 59 carried by the bracket 10, 85 the latter being formed with a guide rib 60 which engages in a guideway 61 formed in the inner side of the bifurcated portion 58 of the foot so as to prevent the twisting of the latter when adjusted. The bifurcated 90 portion 58 of the foot carries a notched plate 62 adapted to straddle an adjusting screw 63 having a threaded inner end 64 engaged in the stud 59, the screw 63 being formed with a reduced portion 65 engaging the 95 notch in the plate 62 and thereby affording a swivel connection for the screw with the foot so that the latter can be vertically adjusted on the turning of the screw. This foot 56 is locked in adjusted position by 100 means of a binding nut 66 threaded on the stud 59, and in this manner the plate 57 can be held in adjusted relation to the knife for throwing off the trimmings cut thereby from the looped fabric carried by the point cylinder D of the machine. 105

The foot 56 carries a shearing plate or shoe 67 which co-acts with the knife for the cutting of the looped fabrics when trimming the same, the brush being designed to 110 clean the seam after the fabrics have been stitched together or united so as to remove waste threads or half loops therefrom resultant from cutting the fabrics by the knife 21 during the working of the attachment. 115

Loosely surrounding the stem or shaft 19 between the eye terminal 15 of the arm 13 and the lever 50, is a collar 68 formed with nibs 69, the latter adapted to work upon the upper edge of the eye terminal 15 for lifting the knife a predetermined distance, the nibs 69 being designed to engage in notches 70 formed in the eye terminal 15 when the knife has been lowered so as to prevent the turning of the collar 68. The said knife is 120 held in lowered position through the medium of a coiled expansion spring 71 surrounding the stem or shaft 19 between the lever 50 and the bearing 20 of the crane 18.

During the operation of the sewing ma- 130

chine the trimming and cleaning attachment will be simultaneously actuated so that the knife 21 will oscillate and likewise the brush 40 whereby the knife will cut the surplus in 5 the fabrics held by the point cylinder, and subsequent thereto the brush will clean the fabrics to remove waste threads or loops cut by the knife prior to the uniting of the fabrics, and in this manner the seamed or looped 10 fabrics will be trimmed at the seams and such seams will be cleaned or the surplus stitches removed so as to avoid the formation of ridges and to prevent surplus waste left in the fabric when sewed together.

15 From the foregoing it is thought that the construction and manner of operation of the device will be clearly understood, and therefore a more extended explanation has been omitted.

20 What is claimed is:—

1. The combination with a sewing machine having a head, of a trimming and cleaning attachment comprising a bracket fixed to the head, a supporting arm mounted upon the 25 bracket and having eye terminals, means for locking the supporting arm against swinging movement, a crane formed on one of the eye terminals, a knife carrying staff journaled in the crane and the eye terminal supporting the same, a gear casing carried by 30 the other eye terminal and having a hollow stem, a beveled gear within the said casing and having a shaft projected through the hollow stem, a brush carrying staff at right 35 angles to the gear shaft, slideable and rocking bearings mounted in the casing and supporting the brush carrying shaft, means for adjusting the slideable bearing, a pinion on the brush carrying shaft and meshing with the 40 gear, a circular brush mounted on the said brush carrying shaft, a hood supported by the sliding bearing and partially inclosing the said brush, and operatively connected levers and links having connection with the 45 knife carrying staff and gear shaft and actuated by the sewing machine for reversely rotating the brush and reciprocating the knife simultaneously with each other.

2. The combination with a sewing machine 50 having a head, of a trimming and cleaning attachment comprising a bracket fixed to the head, a supporting arm mounted upon the bracket and having eye terminals, means for locking the supporting arm against swinging 55 movement, a crane formed on one of the eye terminals, a knife carrying staff journaled in the crane and the eye terminal supporting the same, a gear casing carried by the other eye terminal and having a hollow stem, a beveled gear within the said casing and hav-

ing a shaft projected through the hollow stem, a brush carrying staff at right angles to the gear shaft, slideable and rocking bearings mounted in the casing and supporting the brush carrying shaft, means for adjusting the slideable bearing, a pinion on the brush carrying shaft and meshing with the gear, a circular brush mounted on the said brush carrying shaft, a hood supported by the sliding bearing and partially inclosing the said brush, operatively connected levers and links having connection with the knife carrying staff and gear shaft and actuated by the sewing machine for reversely rotating the brush and reciprocating the knife simultaneously with each other, and a deflector 65 guard plate vertically disposed at one side of the knife and adjustably connected to the bracket.

3. The combination with a sewing machine 80 having a head, of a trimming and cleaning attachment comprising a bracket fixed to the head, a supporting arm mounted upon the bracket and having eye terminals, means for locking the supporting arm against swinging movement, a crane formed on one of the eye terminals, a knife carrying staff journaled in the crane and the eye terminal supporting the same, a gear casing carried by the other eye terminal and having a hollow 85 stem, a beveled gear within the said casing and having a shaft projected through the hollow stem, a brush carrying staff at right angles to the gear shaft, slideable and rocking bearings mounted in the casing and supporting the brush carrying shaft, means for adjusting the slideable bearing, a pinion on the brush carrying shaft and meshing with the gear, a circular brush mounted on the said brush carrying shaft, a hood supported by the sliding bearing and partially inclosing the said brush, operatively connected levers and links having connection with the knife carrying staff and gear shaft and actuated by the sewing machine for reversely rotating the brush and reciprocating the knife simultaneously with each other, a deflector guard plate vertically disposed at one side of the knife and adjustably connected to the bracket, and means connected 100 with the knife carrying staff and co-operative with the crane for adjusting the knife to raised or lowered position.

In testimony whereof I affix my signature in presence of two witnesses.
